E. A. NELSON

INTERNAL COMBUSTION ENGINE

Filed May 1, 1922

Fig. 1.

Patented Sept. 29, 1925.

UNITED STATES PATENT OFFICE.

EMIL A. NELSON, OF HALFWAY, MICHIGAN.

INTERNAL-COMBUSTION ENGINE.

Application filed May 1, 1922. Serial No. 557,607.

To all whom it may concern:

- Be it known that I, EMIL A. NELSON, a citizen of the United States of America, residing at Halfway, in the county of Macomb 5 and State of Michigan, have invented certain new and useful Improvements in Internal-Combustion Engines, of which the following is a specification, reference being had therein to the accompanying drawings.
- 10 In the operation of internal combustion engines, it has been found, that any unburned portions of fuel passing the pistons and dropping into the engine crank case, so dilute the lubricating oil that efficient lubrication is prevented, resulting in injury to the moving parts of the motor. A further source of trouble in the operation of motors of this type is excess of lubricating oil in the cylinders caused by the adherence of the 15 oil to the cylinder wall, which oil is constantly replenished during reciprocation of the pistons, by oil flowing from the piston wall. The excessive amount of oil carried by the cylinder wall is gradually worked up 20 by the reciprocation of the pistons into the combustion chamber, causing rapid formation of carbon which interferes with the efficient operation of the engine.
- An object of the present invention is to 25 overcome these defects and to separate out and catch the unburned portions of fuel remaining in the combustion chamber, in such a manner that the lighter portions of this fuel may be again used as fuel for the engine and the heavier portions may be drawn off. It is also an object to so form 30 the pistons that oil adhering thereto will be directed away from the cylinder wall instead of being deposited thereon, thus reducing the amount of oil on the cylinder 35 surface. A further object is to provide a construction having certain other new and useful features, all as hereinafter more fully described.
- 40 With the above and other ends in view the invention consists in the matters hereinafter set forth and more particularly pointed out in the appended claim, reference being had to the accompanying drawing; in which—
- 45 Figure 1 is a sectional side elevation of a portion of an engine embodying features 40 illustrative of the invention, and
- 50 Fig. 2, a similar view showing the engine piston at the upper end of its stroke in order 55 to more clearly disclose the invention.
- For the purpose of illustration an old and well known type of internal combustion engine is shown in the drawings, said engine comprising a cylinder 1 having the usual water jacket 2 surrounding the same, with 60 the cylinder mounted upon a crank case 3 and a piston 4 reciprocable in the cylinder and having a connecting rod 5 pivotally attached thereto in the usual manner. The features of construction embodying the invention may be embodied in any of the old and well known types of internal combustion engine and it is therefore not the intention to limit the invention to any particular type or general construction of 65 engine.
- 70 One of the features of the present invention relates to the providing of means for removing and collecting unburned portions of fuel remaining in the combustion chamber of an internal combustion engine, thus preventing this residue from passing downward between the piston and cylinder wall into the crank case of the engine. As illustrative of one means for the purpose, a series 75 of small holes or openings 6 is provided in the cylinder wall 7 just below the horizontal plane of the head 8 of the piston 4 when the piston is at the extreme lower end of its stroke. When the piston is at the lower end 80 of its stroke as shown in Fig. 1, these openings 6 are opposite the upper sealing ring 9 of the series of such rings usually provided for sealing the joint between the piston and cylinder walls. Preferably the wall or 85 outer surface of the piston 4 is relieved slightly, as at 10, above this ring 9 and therefore when the piston is in the position shown in Fig. 1 any residue of unburned gasoline remaining in the cylinder above the 90 piston may pass into this narrow passage 10 formed by the relieving of the wall of the piston and find its way downwardly around the ring 9, escaping through the series of 95 openings 6 in the cylinder wall directly opposite the lower side of the ring. These 100 holes 6 open into a chamber 11 formed by carrying the outer wall of the water jacket downward to the base 12 of the cylinder and by providing a draw-off cock 13 for this 105 chamber adjacent the base, this fuel residue may be drawn off at will. Preferably an opening 14 is provided adjacent the upper end of the chamber 11 in the outer wall of the chamber and over this opening is se- 110

cured a pipe 15 which may lead to the carbureter, not shown, or other fuel intake for the engine so that the volatile portions of the fuel residue in the chamber 11 will be 5 drawn off through this pipe by engine operation and again introduced into the cylinder as fuel.

By locating the openings 6 opposite the upper ring 9 when the piston is at the extreme lower end of its stroke, the dwell in the stroke of the piston at this point and the change in the direction of its motion facilitates the escape of any fuel residue past the ring and out through the openings. 10 Further by the location of these openings at the lower end of the piston stroke, they are always sealed by the piston and its rings except when the piston is at the extreme lower end of its stroke and therefore 15 no useful fuel or power is lost through these openings. The cost of manufacture is not materially increased by providing the engine with this chamber 11 as the cylinder block may be readily cast with the outer 20 wall of the water jacket extending to the base of the cylinder, the chamber thus occupying a place around the cylinder which in the usual construction is unoccupied. With this arrangement dilution of the 25 lubricating oil in the crank case by gasoline passing the piston and falling into the crank case is not only effectually prevented but a saving in fuel is made by collecting this residue within the chamber where it 30 is allowed to settle and remains hot and from which the chamber the lighter portions of the fuel may be drawn off and again passed into the engine cylinder, supplementing the regular charges. The heavy 35 portions of the fuel residue in the chamber 11 may be readily drawn off from time to time.

Ordinarily the lower end or skirt portion 15 of the piston 4 is made of uniform diameter throughout its length and therefore upon the upstroke of the piston the lubricating oil splashed into the lower end portion of this skirt by the rotation of the engine cranks, will flow down upon the 20 inner surface of the skirt and pass from the lower end thereof directly to the inner surface of the cylinder wall, supplementing the supply of oil already upon this wall and therefore the cylinder wall receives such a 25 quantity of oil that during reciprocation of the piston this oil will gradually work its way up between the piston and cylinder walls, past the piston rings and finally get into the combustion chamber above the piston where it causes a rapid and excessive 30 formation of carbon upon the head of the piston causing what is known as engine knocking and also causing fouling of spark plugs so that frequent removal and cleaning 35 is necessary. In the present construc-

tion the extreme lower end portion of the skirt 16 is offset inwardly as at 17 thus forming a downwardly extending annular flange 18 at the lower end of the skirt of less diameter than the external diameter of 70 the skirt and also providing a sharp right angle shoulder 19 which serves to scrape any excess of oil from the surface of the cylinder and as the flange 18 has an outer 75 surface leading from this shoulder and free of the wall of the cylinder, the oil scraped from the cylinder wall will be conducted inwardly by adhering to this surface and will collect any drops upon the lower edge of the flange and drop therefrom upon the upstroke of the piston instead of flowing from the lower end of the skirt on to the surface of the cylinder. The supplying of an excessive amount of oil to the cylinder surface below the piston is thus avoided by 80 directing the oil adhering to the piston skirt away from the cylinder surface and therefore sufficient oil is supplied to the cylinder surface to effect efficient lubrication and the passing of oil into the combustion 85 chamber is prevented. 90

The combining of means for removing and collecting unburned fuel residue with the means for directing oil away from the cylinder surface, provides in a simple and efficient manner an engine construction wherein most of the troubles common to internal combustion engines are eliminated and a very material saving is effected in 95 both fuel and lubricating oils. 100

Obviously changes may be made in the construction shown and described, within the scope of the appended claim without departing from the spirit of the invention, and I do not therefore limit myself to the 105 particular form or arrangement shown.

What I claim is:—

In an internal combustion engine, the combination of an upright cylinder with a crank case at the lower end of said cylinder, and a piston reciprocable in said cylinder, said cylinder being formed with an annular chamber surrounding the lower end portion of the cylinder and the cylinder wall being formed with openings adjacent and below the plane of the upper end of the piston head when said piston is at the lower end of its stroke, means for drawing vapor from the upper part of said chamber rising from the residue of fuel caught therein, said piston being formed with a groove adjacent its upper end and the upper end of said piston above said groove being of reduced diameter, and a packing ring in said groove in the piston, said ring being located opposite the openings in the cylinder wall when the piston is at the lower end of its stroke. 115 120 125

In testimony whereof I affix my signature.

EMIL A. NELSON.
